COLLAPSIBLE CARTON

Edwin L. Arneson, Morris, Ill., assignor to Federal Paper Board Company, Inc., Bogota, N.J., a corporation of New York

Application January 29, 1958, Serial No. 711,924

3 Claims. (Cl. 229—31)

This invention relates to packaging and is more particularly concerned with improvements in a collapsible tray-like receptacle or carton section which is formed of paperboard or similar material and which is adapted for use in packaging merchandise of various kinds.

It is a general object of the invention to provide a collapsible tray-like carton section which is formed from a blank of paperboard or similar material wherein greater strength and rigidity is provided in the set up carton and wherein an improved method of forming the carton is employed which facilitates the manufacture of the same.

It is a more specific object of the invention to provide an open top tray-like carton section formed from a paperboard blank which is cut and scored to provide, when erected, a bottom wall, upright side and end walls and a foldable end panel structure for connecting the side and end walls at each of the corners thereof which end connecting structure comprises two panels of generally triangular form which are hingedly connected to fold upon each other and which have adjacent edges hinged to the adjacent corner forming edges of adjoining side and end walls, the triangular panel which is connected to the end wall being folded inwardly upon the inside face of the end wall and being secured thereto and having a relatively narrow integral flap at its top edge which is folded down upon the face thereof and secured thereto.

It is a further object of the invention to provide a collapsible tray-type carton member which is formed from a generally rectangular paperboard blank cut and scored to divide the same into a series of connected panels which provide, when erected, upstanding side and end walls hingedly connected to the peripheral edges of a bottom wall and end connecting structures at each corner, the side walls being of a depth which is greater than half the width of the bottom wall and the end connecting structures each comprising a generally rectangular section which is divided by a diagonal fold line into two generally triangular panels with the panels being hinged to the adjoining side and end walls and with the panel which is hinged to the end wall being adapted to be adhesively secured to the inner face of the end wall and having a flap hinged to the upper edge thereof which is foldable into face engaging relation therewith and which is adapted to be secured thereto to provide a triple thickness of material along the outer margin of the end wall which insures adherence of the triangular end connecting panel to the end wall when the side walls of the carton are folded into collapsed condition on the bottom wall and the collapsed carton is passed between pressure rollers in a standard folding and gluing machine on which the cut and scored blank is folded and glued.

It is a further object of the invention to provide improvements in the method of manufacturing a collapsible tray-type carton of the character described on standard folding and gluing machines wherein reinforcing flaps are provided on the top edges of the carton corner connecting structures which are folded over onto the con-

2

necting panels and adhered thereto during the folding and gluing operations to provide increased thickness of material in portions of the end wall areas so that the adhesive coated panels in these areas will be subject to sufficient pressure while passing between the pressure rollers of the folding and gluing machines to insure that the adhesive will be effective and bond the panels to each other in these areas as it sets during the passage of the carton between the pressure rollers.

10 These and other objects and advantages of the invention will be apparent from a consideration of the carton and the method of forming the same which is shown by way of illustration in the accompanying drawings wherein:

15 Figure 1 is a perspective view of a tray-type carton member having incorporated therein the principal features of the invention;

Figure 2 is a fragmentary cross section taken on the line 2—2 of Figure 1, to a greatly enlarged scale;

20 Figure 3 is a plan view of a paperboard blank which is cut and scored to provide the carton illustrated in Figure 1;

25 Figure 4 is a fragmentary perspective view of an end portion of the carton in the folded and collapsed condition prior to being set up; and

Figure 5 is a perspective view, largely schematic, illustrating the method of folding and gluing the cut and scored blank to produce the carton in a collapsible condition.

30 Referring to Figures 1 and 2, there is illustrated a carton member 10 which is in the form of an open top tray and which is adapted to form half of a two part telescoping carton, the other half (not shown) being of similar tray-like form and having slightly different dimensions so as to telescope therewith. The details of the tray 10 will be best understood by reference to the manner in which a blank of paperboard stock is cut and folded to provide the panels for forming the bottom and the upstanding wall structure associated therewith.

35 Referring then to Figure 3 of the drawings, there is illustrated a blank 11 of paperboard or similar sheet material which has sufficient stiffness to be self sustaining and which is cut and scored to provide a series of hingedly connected wall forming panels. The blank 11 when cut and scored as shown in Figure 3, is symmetrical about longitudinal and transverse center lines *a—a* and *b—b*. It is divided by the transversely spaced, longitudinally extending, parallel score lines 12 and 13 which are on opposite sides of the longitudinal center line *a—a* and parallel therewith and which define the side edges of a bottom and end wall forming portion of the blank.

40 Longitudinally spaced, transversely extending, parallel score lines 14, 15 and 16, 17 cooperate with the score lines 12 and 13 to divide the center section of the blank into a bottom forming panel 18, adjoining end wall forming panels 19 and 20 and outer end wall reinforcing panels 21 and 22 which are hingedly connected to the inner end wall forming panels 19 and 20, respectively, on the transverse score lines 14 and 17 and which have at their terminal end margins relatively narrow flaps 23 and 24 separated from the panels 21 and 22, respectively, by transverse score or perforation lines 25 and 26 which are parallel with the score lines 14 and 17 and which are spaced inwardly a short distance from the end edges of the blank.

45 The longitudinal score lines 12 and 13 separate from the central section of the blank side marginal sections 27 and 27' which extend in a transverse direction outside of the score lines 12 and 13 and which are cut and scored in an identical manner to provide the side walls 50 for the carton and also foldable panel structures for connecting the side and end walls at each corner of the car-

55

70

ton. Since the two side marginal sections 27 and 27' of the blank are identical only one will be described, the corresponding elements on the other being indicated by the same numerals primed. The side marginal section 27 is subdivided by the longitudinally extending score line 28, which is parallel with and spaced outwardly of the score line 12, into inner and outer panels and the latter is subdivided longitudinally by transversely extending end portions 29 and 30 of the transverse score lines 15 and 16, which terminate adjacent opposite ends of the longitudinal score line 28. The blank section 27 is also cut away at both its outside corners so that the score lines divide it into a main side wall panel 31, a side wall reinforcing panel 32 and two corner connecting panel structures 33 and 34, which are located at the opposite ends of the main side wall panel 31 and which are subdivided in an identical manner. The inner or main side wall panel 31 is defined by the score lines 12, 28, 29 and 30 and the outer or reinforcing side wall panel 32 is hinged to the same along the score line 28 which forms the top edge of the side wall when the carton is set up. The reinforcing panel 32 is substantially the same width or depth as the side wall panel 31 but is cut away at the ends so that it is slightly less in the longitudinal dimension. The panel forming portions of the side marginal section 27 which provide the corner connecting structures 33 and 34 are formed in an identical manner and only one will be described in detail. The corner connecting portion 34 of the blank lies outside of the end portions 30 and 35 of the intersecting transverse and longitudinal score lines with the corner of the blank being cut away to remove the material at the end of the side wall reinforcing panel 32 and part of the material at the end of the inner end wall panel 22. The remaining material is divided by a diagonal score or perforation line 36 to provide two panels 37 and 38 which are of generally triangular shape with their inner adjacent edges defined by the score lines 30 and 35, respectively, so that the two triangular panels 37 and 38 are hinged along adjoining edges to the end and side wall panels 20 and 31, respectively, on the score lines 35 and 30. Outer portions of the panels 37 and 38 are cut away along the diagonal line 39 which is substantially perpendicular to the diagonal hinge line 36 and along the longitudinal line 40 which is parallel with the corner forming score line 35. The triangular panel 37 which is hinged to the end of the end wall panel 19 is scored or perforated on the transverse line 41 which is substantially aligned with the transverse score line 17 to form on the edge thereof a reinforcing flap or tab 42, the latter being taken from the material adjoining the end of the end wall panel 22 and being hinged on the score line 41. The outside cutting line 40 is located relative to the longitudinal score line 12 so that the distance between these two lines does not exceed one-half the distance between the longitudinal score lines 12 and 13.

The cut and scored blank 11 is provided with adhesive and folded into the collapsed condition in which it is supplied to the user on conventional straight line folding and gluing machines, portions of which are illustrated schematically in Figure 5 of the drawings. The blank 11 is first advanced in the direction of its longitudinal axis and glue is applied as illustrated to the faces of the side wall panels 31 and 31' and triangular sections 37 of each of the corner connecting panels. As the blank is advanced in the longitudinal direction the side wall reinforcing panels 32 and 32' are folded about the score lines 28 and 28' by the folder plates or plows indicated at 43 onto the adhesive covered faces of the inner side wall panels 31 and 31'. The panels 31 and 31' are then folded successively about the score lines 12 and 13 by the folder plates at 44 to bring them into overlying relation with the bottom wall panel 18 and with their margins overlapping. This operation brings the glue coated faces of the corner connecting panels 37 into

engagement with the inner faces of the end wall forming panels 19 and 20 to which they are to be adhered, with the reinforcing tabs 42 overlying the end wall panels 21 and 22. The direction of movement of the blank is then changed so that it advances at a right angle to the original direction of movement and glue is applied to the exposed faces of the reinforcing flaps 42. Thereafter the end wall panels 21 and 22 are folded upwardly and inwardly about the score lines 14 and 17, respectively, by the folder plates at 45 which folds the reinforcing flaps 42 over onto the faces of the triangular panels 37. This provides an additional thickness of material in the areas adjacent the score lines 14 and 17 which results in sufficient pressure being applied by the pressure rollers at 46 to adhere the panels 37 to the end wall panels, particularly at the corners, when the glue sets, the flaps 42 compensating for the extra thickness of material, which results as indicated at 47 in Figure 4, from the overlapping of the panels 38 in the area adjacent the fold lines 15 and 16. The flaps 42, of course, reinforce the top edge portion of the end walls in the set up condition of the carton.

In the form of the carton illustrated the reinforcing flaps 42 are hinged to the corner connecting panels 37. Alternately, the reinforcing flaps may be hinged to the end wall panels 21 and 22 and adhered to the same. Also, the size of these panels may be varied so long as they serve to compensate for the extra thickness of material at 47.

While specific materials and particular details of construction are referred to in describing the form of the carton illustrated, it will be understood that other materials and equivalent details of construction may be resorted to within the spirit of the invention.

I claim:

1. A collapsible tray type container formed from a paperboard blank which is cut and scored to provide a series of connected panels forming, when erected, a rectangular bottom wall, upstanding side and end walls hinged to the peripheral edges of said bottom wall, and connecting panels at each corner joining the adjacent upright corner forming edges of said side and end walls, said connecting panels at each corner comprising two hingedly connected generally triangular panel portions foldable upon each other and having adjoining edges connected to the adjacent edges of adjoining side and end walls, the triangular panels which are connected to the end wall being folded against the inner face of the end wall and being adhesively secured thereto, said corner connecting panels overlying the end walls in the collapsed and flattened condition of the carton, the triangular panels which are connected to the side walls each having a dimension along the edge which is connected to the side wall which is greater than one half the dimension of the end wall along that edge of the end wall which is hinged to the bottom wall whereby said triangular panels have overlapping portions forming a double thickness of material, and with the triangular panels which are connected to the end walls each having a dimension in the direction normal to the corner forming edge of the end wall which does not exceed one half the dimension of the end wall in the corresponding direction whereby said triangular panels lie in the same plane, and relatively narrow reinforcing flaps secured in overlying relation on the triangular panels which are connected to the end walls, said reinforcing flaps having a dimension in the direction normal to the corner forming edge of the end wall which does not exceed the corresponding dimension of the triangular panel to which they are secured so as to form with the same a double thickness of material in areas of the end wall outside of the overlapping portions of the triangular panels which are connected to the side walls.

2. A blank for a collapsible tray type container, said

blank being cut and scored to divide the same into a series of connected panels forming, when erected, a rectangular bottom wall and upstanding side and end walls hinged to the peripheral edges of said bottom wall, said blank being divided by parallel transversely spaced, longitudinally extending score lines into a center section and two side marginal sections, the center section of said blank being subdivided by parallel, longitudinally spaced, transverse score lines into a bottom wall panel, end wall panels adjoining opposite ends of said bottom wall panel, and end wall reinforcing panels adjoining said end wall panels, the side marginal sections of said blank being divided into side wall panels hinged along opposite side edges of the bottom wall panel, side wall reinforcing panels hinged to the opposite edges of the side wall panels, and corner connecting panels joining adjacent end edges of said side and end wall panels at each corner of the blank, said connecting panels at each corner comprising two generally triangular portions on opposite sides of a diagonal score line which extends diagonally outwardly of the corner of the bottom wall panel, the triangular panel portion which adjoins the side wall panel having a dimension transversely of the blank which exceeds half the corresponding dimension of the end wall, the triangular panel portion which adjoins the end wall panel having a dimension transversely of the blank which does not exceed half the corresponding dimension of the end wall panel, and a relatively narrow reinforcing flap extending along the transverse edge of said last mentioned triangular panel portion and which is adapted to be folded down over the inside face of said last mentioned triangular panel portion when the blank is folded to form the carton.

3. A method of forming a collapsible tray type container from a paperboard blank which comprises cutting

and scoring the blank to provide a series of connected wall forming panels, including a rectangular bottom wall panel, upstanding side and end wall panels hinged on longitudinal and transverse score lines to the peripheral edges of said bottom wall panel, and foldable corner connecting panels having portions which overlap each other when they are in overlying relation on the end wall panels in the collapsed condition of the carton, said connecting panels at each corner comprising two panel members of generally triangular form which are hinged upon each other about a diagonal fold line and which have adjoining edges hinged to the corner forming edges of adjacent side and end walls, providing a reinforcing and thickness increasing tab at each outer corner of each end wall panel, applying an adhesive to the faces of the corner connecting panels which are hinged to the end walls, folding the side wall panels and the corner connecting panels over upon the bottom wall and end wall panels while moving the blank in a longitudinal direction, moving the partially folded blank in a transverse direction and applying an adhesive to the exposed faces of the reinforcing and thickness increasing tabs, folding the reinforcing and thickness increasing tabs over upon the corner connecting panels which are hinged to the end walls so that they are positioned in areas adjoining the portions of said panels which are overlapped, and passing the portions of the folded blank having said reinforcing and thickness increasing tabs thereon between pressure rollers.
